ROBERT H. PLASS, OF UPPER MONTCLAIR, NEW JERSEY, ASSIGNOR TO THE CHAPAL-DONNER CORPORATION, OF NEWARK, NEW JERSEY, A CORPORATION OF NEW JERSEY

FUR CUTTING MACHINE

Application filed June 20, 1931. Serial No. 545,793.

This invention relates to improvements in fur cutting machines for cutting animal pelts to remove fur from the skin thereof; and the invention has reference, more particularly, to means for preventing turbulent air currents at the cutting point of the machine which, if uncontrolled, result in both sucking away with skin slivers or chips valuable proportions of the severed fur and the blowing of such severed fur into the surrounding atmosphere, all of which results in considerable waste of fur and substantially diminishes the available severed fur output of the machine.

1. Fur cutting machines, as commonly used in the hat manufacturing industry, comprise a rapidly rotated cutting drum carrying radially projecting cutting blades which co-operate with a stationary bed knife over which the pelts are fed, so that as chips or slivers of skin are cut from the pelts, the fur will be severed therefrom to fall or be carried away from the exterior side of the bed knife. Usually the cutting drum is enclosed in a covering casing or hood. Owing to the rapid revolution of the cutting blades, the same act upon the air within the casing or hood in the manner of impeller blades, resulting in more or less forceful displacement of air with consequent production of uncontrolled air currents or eddies in the vicinity of the bed-knife. Such air currents or eddies tend to disturb the severed hair, both blowing the same about and sucking the same into the hood to be discharged as waste with the skin chips or slivers, all of which results in no inconsiderable loss of severed fur and wastefully diminishes the available fur output of the machine.

2. It is the principal object of this invention to provide means calculated to prevent turbulent and fur disturbing air currents and eddies in the vicinity of the cutting point of the machine; and to this end the invention provides a novel construction and arrangement of casing or hood for enclosing the rotary cutting drum of the machine, said casing or hood having means for discharging air currents produced by the revolving cutting blades of said drum in such manner and

in such relation to the cutting point of the machine, that turbulent air currents and eddies in the vicinity of the cutting point of the machine are substantially prevented, so that undesired disturbance and uncontrolled displacement of severed fur to be discharged from the machine is avoided, and consequently a maximum output of severed fur is attained during operation of the machine with minimum of waste or lost fur.

3. Other objects of this invention, not at this time more particularly enumerated, will be understood from the following detailed description of the same.

4. An illustrative embodiment of this invention is shown in the accompanying drawings, in which:—

5. Fig. 1 is a side elevation of a portion of a fur cutting machine, including the cutting mechanism and the novel enclosing casing or hood having air control means according to this invention; Fig. 2 is a plan view of the same; Fig. 3 is a vertical longitudinal section through the same; and Fig. 4 is an enlarged fragmentary vertical longitudinal section to illustrate the mode of operation thereof when cutting fur from a pelt.

6. Similar characters of reference are employed in the above described views to indicate corresponding parts.

7. Referring to said drawings, the reference character 5 indicates the side frames of a fur cutting machine, in which are formed bearing members 6 to journal the drive shaft 7 of a cutting drum 8. Cooperating with said bearing members 6 are bearing caps 9. Extending between said side frames 5, adjacent to the forward side of said cutting drum 8, is a suitable bed-knife support 10 having a suitable clamp-plate 11. Adjustably mounted between said support 10 and clamp-plate 11 is a bed-knife 12 having an upwardly projected cutting edge extending across the forward side of said cutting drum 8. Said cutting drum is provided with a plurality of circumferentially spaced, radially projecting cutting blades 13, the cutting edges of which are moved by the rotation of the cutting drum 8 in downward passing shearing contact with and relation to the cutting edge of 100

said bed-knife 12. Said cutting drum 8 may be driven, at high speed, through its shaft 7 from any suitable source of power and by suitable transmission means (not shown).

5 The cutting blades 13 are preferably of the helical form usually employed in fur cutting machines.

10 Journaled in and extending between side plates 14, which are connected with said side frames 5 to form parts of the machine framework, are parallel shafts 15 and 16, which respectively carry the members of a pair of pelt feed rollers 17 and 18. Said feed rollers are disposed to lie in front of and adjacent to 15 the cutting edge of said bed-knife 12, so as to grip and advance a pelt over the latter, and subject to the cutting action of the cutting blades 13 of the rotating cutting drum 8. Said shafts 15—16 are intergeared for opposite rotation of the feed rollers 17—18 by 20 gearing 19, and one of said shafts, as 15, is suitably driven at desired speed from a source of power by transmission gearing, shown in part at 20.

25 Arranged to extend over and enclose the upper part of said cutting drum 8 is a casing or hood, the same comprising end-plates 21, cut away at 22 to bridge over the shaft 7 adjacent to the ends of the cutting drum, and 30 further cut away at 23 to extend over and clear the feed rollers 17—18. Extending between said end-plates 21 above and around the upper side of the cutting drum 8 is a casing top 24 of substantially semi-cylindrical shape, and disposed substantially concentric to the axis of said cutting drum 8. The forward margin of said casing top 24 terminates above and spaced from the feed rollers 17—18, so as to provide an air escape 35 opening 25 above the cutting point of the machine. Secured to and extending between the upper portions of said end plates 21, is an auxiliary casing comprising a top wall 26 which is spaced above said casing top 24, and 40 a back wall 27 which joins and is secured to said casing top 24. The interior of said auxiliary casing provides an air discharge chamber 28. Formed in said back wall 27 is a discharge opening 29 which communicates with 45 a conduit 30. Said conduit 30 is, in operation, preferably connected with an air exhaust fan or pump (not shown). Connected with and extending between the forward margins of the upper portions of said end- 50 plates 21, is a deflector plate 31, the marginal portion 32 of which is in-turned to pass over the feed rollers 17—18, with its inner edge spaced from and somewhat inwardly offset 55 from the forward edge of said casing top 24 to form with the latter said air escape opening 25. The marginal portion 32 of the deflector plate 31 projects into the path of air movement within the casing 24 as induced by the revolution of the cutting blades 13, 60 whereby the forwardly driven air is large-

ly deflected and vented through the escape opening 25 before it reaches the vicinity of the front opening contiguous to the cutting point of the machine. Depending from said inner edge of said marginal portion 32 of deflector plate 31, is a skirt flange 33 which terminates close to the upper feed roller 18 and which forms an air stop or baffle. The upper portion 34 of said deflector plate 31 is secured to the front margins of said end- 70 plates 21, but preferably terminates short of the front margin of said auxiliary casing top wall 26, to provide an air intake opening 31 leading into the interior of said air discharge chamber 28 above said air escape 80 opening 25.

Said casing or hood is adjustably related to the framework of the machine, so as to be capable of being positioned to conform to adjusted relations of the cutting drum 8 and feed rollers 16—17. To this end said casing or hood is slidably movable forward and backward upon the side frames 5. To effect such movements, and to retain the casing or hood in the position to which it has been adjusted by given movement thereof, said end plates 21 are provided with rearwardly extending arms 36 having upwardly indented yoke slots 37. Fixed upon the rearward portions of said side frame 5 is a transversely disposed bridge plate 38, the end portions of which respectively overhang the respective side frames 5. Slidably supported for longitudinal movement along the underside of the overhanging ends of said bridge plate 100 38 are slide-pieces 39 having upwardly projecting perforate bearing arms 40 at their forward ends. Said slide-pieces 39 are supported by bolts 41, which extend through slots 42 therein, to screw into said bridge plate ends. Fixed to and extending between said arms 40 of the slide-pieces is a cross-bar 43 over which are engaged said yoke slots 37 of the arms 36 of the casing or hood end plates, thereby coupling said casing or hood to said slide-pieces. Secured to said bridge plate 38 are depending perforate lugs 44 through which respectively extend screw shanks 45 which respectively project from the rearward ends of said slide-pieces 110 39. Threaded on said screw shanks 45 respectively on opposite sides of said lugs 44 are adjusting nuts 46 and 47. To adjustingly move the casing or hood forwardly, the nuts 47 are loosened or turned back from the lugs 44 whereupon the nuts 46 are screwed 120 onward to move the slide-pieces forward and thus transmit through cross-bar 43 forward adjusting movement to the casing or hood. To adjustingly move the casing or hood rearwardly, the nuts 46 are screwed back away from lugs 44, and the nuts 47 screwed forwardly on the screw shanks to draw rearwardly the slide pieces and the connected casing or hood. The casing or hood is also ca- 125 130

5 pable of vertical swinging adjustment relative to said cross-bar 43 as fulcrum to adjust the position of forward air escape passage relative to adjusted positions of cutting drum and feed rollers. To attain such 10 adjustments stationary up-standing screw threaded posts 48 are fixed to the bearing caps 9 to extend upwardly adjacent to the exterior sides of the casing or hood end plates

15 21. Threaded on said posts 48 are supporting nuts 49 which supportingly bear against the underside of shoulder projections 50 which extend outwardly from said end plates 21. Said posts 48 have threaded shanks 51 20 of reduced diameter to receive keeper nuts 52 which may be screwed down against the top of the casing or hood to hold the same in such adjusted position as may be determined by the supporting nuts 49.

25 20. In the operation of the machine, the pelt, fur side down, is passed between the feed rollers 17—18 which grip and advance the same toward the bed-knife 12, the fur being combed or laid back by the forward movement of the pelt, whereby the bases of the fur filaments are exposed to the cutting action of the revolving cutting blades 13, which, as the same pass shearingly along the bed-knife 12, operate to sheer off a sliver or chip 30 of the pelt skin, thereby at the same time severing from the skin sliver or chip the fur filaments close to their roots.

35 Owing to the rapid rotation of the cutting drum 8, the projecting cutting blades 13, revolved thereby, drive the air confined within the casing, by which the cutting drum is usually enclosed, toward the front opening through which the pelt is introduced across the bed-knife. Such enforced air movement 40 produces strong and turbulent air currents and eddies, which tend, forcefully, both to puff out through said front opening, and at times create sucking effects at such point, all of which tends to more or less disturb the 45 severed fur, blowing some externally away into the atmosphere about the machine, and sucking some with the skin chips and scrap interiorly into the casing, all of which depletes the normal output of the machine and 50 results in no inconsiderable waste of fur.

55 By means of the novel hood structure according to the present invention, the undesirable turbulent air currents, especially at the opening contiguous to the bed-knife, are prevented, and waste of fur avoided. This novel hood structure functions as follows:—

60 As air confined within the cutting drum compartment is driven forwardly by the revolving cutting blades 13, the major portion of such air infringes upon the deflector plate 31 and is diverted through the escape opening 25 before it reaches the vicinity of the front opening through which the pelt is passed to the cutting point of the machine. 65 In this manner, the air is controlled, and

turbulent air currents and eddies at the cutting point of the machine are so reduced as to eliminate risk of disturbing severed fur, whereby the latter is permitted to fall freely away from the cutting point so as to be collected for use in any suitable manner. In this way loss or waste of fur is substantially avoided, and the operation of the machine is brought to high efficiency, resulting in maximum output of severed fur.

70 Preferably the air discharged through the escape opening 25 is passed upwardly into the air discharge chamber 28, and since this air usually contains more or less dust, which is produced by operation on the pelts, the suction applied to the conduit 30, by a suitably driven fan or pump, not shown, serves to carry away such dust-laden air and prevents the same from being discharged into the room in which the machine or machines are operated. Preferably the air discharge chamber 28 is provided with the intake opening 35 open to the atmosphere, so that a certain amount of air is drawn through this opening 35 into and through the discharge chamber 28, thus preventing undue suction effect at the air escape opening 25, and thereby avoiding undue agitation or insucking of air at the front opening of the machine below the escape opening 25.

75 95 As the knives of the cutting drum wear, making necessary the customary relative adjustments of cutting drum, bed-plate and feed rollers, the hood structure may likewise be adjusted to conform to the adjusted positions of these parts by the above described hood adjusting mechanism provided for the purpose.

100 I am aware that many changes could be made in the above described structures, as well as in the details of the construction thereof, without departing from the scope of this invention as defined in the appended claims; it is therefore intended that all matter contained in the above description or 105 shown in the accompanying drawings shall 110 be interpreted as illustrative and not in a limiting sense.

115 1. In a fur cutting machine, including a rotatable cutting drum, cooperating bed-knife and pelt feed means; an enclosing hood structure for said cutting drum having a front opening contiguous to said bed-knife and feed means to give access to a pelt fed to the bed-knife by said feed means, means 120 providing an air escape opening in advance of said front opening, and means to deflect air impelled toward said front opening by said cutting drum through said escape opening.

125 2. In a fur cutting machine, including a rotatable cutting drum, cooperating bed-knife and a pelt feed means; an enclosing hood structure for said cutting drum having a front opening contiguous to said bed-knife 130

and feed means to give access to a pelt fed to the former by the latter, said hood structure having an air escape opening in advance of said front opening, and a deflector means bounding one side of said opening and projecting into the path of air moved toward said front opening by said cutting drum.

3. In a fur cutting machine, including a rotatable cutting drum, cooperating bed-knife and pelt feed means; an enclosing hood structure for said cutting drum having a front opening contiguous to said bed-knife and feed means to give access to a pelt fed to the former by the latter, said hood structure having an air escape opening in advance of said front opening, a deflector means bounding one side of said escape opening, and means providing an air suction chamber to which said deflector means leads to connect said escape opening in communication therewith.

4. In a fur cutting machine, including a rotatable cutting drum, cooperating bed-knife and pelt feed means; an enclosing hood structure for said cutting drum having a front opening contiguous to said bed-knife and feed means to give access to a pelt fed to the former by the latter, said hood structure having an air escape opening in advance of said front opening, a deflector means bounding one side of said escape opening, means providing an air suction chamber to which said deflector means leads to connect said escape opening in communication therewith, and said air suction chamber having an air intake open to the atmosphere to modify the suction effect at said escape opening

5. In an enclosing hood structure for fur cutting machines as defined in claim 1, means for adjusting said hood according to relative adjusted positions of the fur cutting and pelt feeding mechanism.

6. In an enclosing hood structure for fur cutting machines as defined in claim 2, means for adjusting said hood according to relative adjusted positions of the fur cutting and pelt feeding mechanism.

7. In an enclosing hood structure for fur cutting machines as defined in claim 3, means for adjusting said hood according to relative adjusted positions of the fur cutting and pelt feeding mechanisms.

8. In an enclosing hood structure for fur cutting machines as defined in claim 4, means for adjusting said hood according to relative adjusted positions of the fur cutting and pelt feeding mechanisms.

In testimony, that I claim the invention set forth above I have hereunto set my hand this 9th day of June, 1931.

ROBERT H. PLASS.
